CLAIM

We claim the ornamental design for a handheld electronic device skin, as shown and described.

DESCRIPTION

FIG. 1 is a front perspective view of a handheld electronic device skin;

FIG. 2 is a back perspective view of the handheld electronic device skin;

FIG. 3 is a front elevational view thereof;

FIG. 4 is a back elevational view thereof;

FIG. 5 is a left elevational view thereof;

FIG. 6 is a right elevational view thereof;

FIG. 7 is a top plan view thereof; and,

FIG. 8 is a bottom plan view thereof.

The broken lines shown in the drawings of the handheld electronic device skin are for the purpose of illustrating portions of the article and form no part of the claimed design.
